US0D1084754S

(12) **United States Design Patent** (10) **Patent No.:** **US D1,084,754 S**
(45) **Date of Patent:** **** Jul. 22, 2025**

(54) **LID WITH STRAP**

(71) Applicant: **Factory Enova, LLC**, Fountain Valley, CA (US)

(72) Inventors: **Seth Imo Inyang**, Anaheim, CA (US); **Vinh Lieu**, Fountain Valley, CA (US); **Feifei Wang**, Tongkang (CN); **Jessica Anna Inyang**, Anaheim, CA (US)

(73) Assignee: **Factory Enova LLC**, Anaheim, CA (US)

(**) Term: **15 Years**

(21) Appl. No.: **29/901,890**

(22) Filed: **Sep. 6, 2023**

(51) LOC (15) Cl. **07-02**
(52) U.S. Cl.

USPC **D7/392.1**

(58) **Field of Classification Search**

(57) **CLAIM**

The ornamental design for a lid with strap as shown and described.

DESCRIPTION

FIG. 1 is a perspective view of a lid with strap, showing the spout in a closed position, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a lid with strap, showing the spout in an opened position;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines are shown for the purpose of illustrating parts of the article that form no part of the claimed design. The strap feature is shown with a symbolic break in its length. The appearance of any portion of the article between the break lines forms no part of the claimed design.

1 Claim, 8 Drawing Sheets
